UNITED STATES PATENT OFFICE

KARL M. STONE, OF MERRICK, NEW YORK, ASSIGNOR TO STONE SHOE COMPANY, INC., OF NEW YORK, N. Y., A CORPORATION OF NEW YORK

MULE

Application filed July 23, 1929. Serial No. 380,353.

This invention relates to footwear and has more particular reference to that type of ladies' boudoir slippers which are commonly known as mules.

5 Due to the difficulty of retaining the same on the foot, mules have been recently provided with a retaining strap for engagement around the upper portion of the heel, and while these straps serve the purpose of retaining the mule on the foot, they have been found to be open to certain objections, notably their failure to hold the rear portion of the vamp against gapping.

10 The present invention therefore, aims to improve the structure of a mule by providing a heel strap which is directly attached to or which may form an integral part of the vamp, whereby said strap in performing its function of retaining the mule in place on the 15 foot, also serves as a means for causing the rear portion of the vamp to hug and snugly fit the foot to provide gapping thereof.

15 The invention furthermore aims to provide a mule provided with a heel strap which is constructed and attached in such a manner as to cause the same to assume a normal position which renders the mule more attractive in appearance and hence more salable when displayed for sale.

20 Other objects of the invention reside in the simplicity of construction, the economy with which the same may be produced, and the general efficiency derived therefrom.

25 With the above-recited and other objects in view, reference is had to the following description and accompanying drawings, in which there is exhibited one example or embodiment of the invention, while the claims define the actual scope of the same.

30 In the drawings,

Figure 1 is a perspective view of a mule constructed in accordance with the invention;

Fig. 2 is a plan view thereof, parts being broken away to disclose the underlying structure;

Referring to the drawings by characters of reference, the mule includes the sole A, the vamp B and the heel C. The heel strap D is constructed of a length or strip of material 45 which is carried by the rear portions E of

the vamp and which is arranged to snugly fit around the upper portion of the heel of the foot when the mule is applied. While it is to be understood that the heel strap D may form an integral part of the vamp, the same 55 is illustrated as constructed separately therefrom, in which instance the terminals F of the heel strap are stitched to the rear portions E of the vamp as illustrated.

In use, the heel strap in performing its function of retaining the mule by engaging around the upper portion of the heel, exercises a pull on the rear of the vamp which tends to cause the rear portions E to adhere to or snugly fit the foot. In addition to this, the heel strap receives sufficient support by being secured to the rear portions of the vamp throughout the height of the same, to cause said strap to assume its normal position when not in use, whereby when displayed for sale, the mule offers a more attractive and salable appearance to prospective purchasers. It will also be observed that the lower edge G of the heel strap is shaped to conform generally to the configuration of the upper edge 70 of the quarter part of the vamp whereby to lend generally to the attractiveness of the mule when worn or displayed.

I claim:

1. A mule including an inelastic, semi-rigid 80 heel strap for engaging around the upper portion of the heel of the foot when applied thereto, said strap being secured directly to the rear portions of the vamp and to the sole.

2. A mule including a heel strap for engaging around the upper portion of the heel of the foot when applied thereto, said strap being secured to the rear portions of the vamp and to the sole at adjacent side and end edges of its terminal.

KARL M. STONE.
